UNITED STATES PATENT OFFICE

101,463

DESIGN FOR A SHOE OR SIMILAR ARTICLE

William H. Joyce, Pasadena, Calif., assignor to
Pasadena Slipper Co., Pasadena, Calif., a cor-
poration of California

Application June 27, 1936, Serial No. 63,526

Term of patent 7 years

To all whom it may concern:

Be it known that I, William H. Joyce, a citizen of the United States, residing at Pasadena, in the county of Los Angeles and State of California, have invented a new, original, and ornamental Design for a Shoe or Similar Article, of which the following is a specification, reference being had to the accompanying drawing, forming a part thereof.

Fig. 1 is a perspective view, illustrating one side of a shoe or similar article showing my new design; and

Fig. 2 is a perspective view of the opposite side of the shoe or similar article shown in Fig. 1.

The characteristic features of my design reside in a slipper comprising the upper, a relatively

thick mid-sole, the shape of which includes a relatively thick portion at the heel of the slipper which tapers towards the arch, and thence is continuously carried forward to the extreme end of the toe of substantially constant thickness from the arch portion to the toe, the portion of the mid-sole between the arch and the toe being narrower than the portion at the heel, and an additional element consisting of a relatively thin, flat out-sole member at the extreme lowermost portion of the slipper.

I claim:

The ornamental design for a shoe or similar article, as shown and described.

WILLIAM H. JOYCE.
